UNITED STATES PATENT OFFICE.

MILTON L. DODGE, OF NEWBURYPORT, MASSACHUSETTS.

TURN-SHOE AND METHOD OF MAKING THE SAME.

1,224,081.

Specification of Letters Patent. Patented Apr. 24, 1917.

Application filed July 24, 1916. Serial No. 110,855.

To all whom it may concern:

Be it known that I, MILTON L. Dodge, a citizen of the United States, residing at Newburyport, in the county of Essex and 5 State of Massachusetts, have invented new and useful Improvements in Turn Shoes and Methods of Making the Same, of which the following is a specification.

This invention relates to the art of manufacturing turn shoes, and has for its object 10 the provision of a shapely shoe, as well as a reduction in the time required for the complete manufacture thereof.

More particularly, the object of the invention is to provide a method or process of manufacture by which a shoemaker may employ an initially molded toe box, in turn shoes, without tempering or softening it, or 15 distorting the shape thereof. The importance of this will be readily appreciated by those skilled in the art, since tempering a toe box requires that the box must subsequently be shaped and must be given a relatively long time to dry, before the final operations in the manufacture of the shoe can 20 be properly completed.

On the drawings,—

Figure 1 illustrates a partially lasted turn shoe, with the lining of the upper turned 30 back at the toe.

Fig. 2 illustrates in section the front end of the shoe after it has been turned, and prior to the insertion of the box.

Fig. 3 illustrates the operation of inserting the box while the toe end of the lining 35 is drawn heelward.

Fig. 4 shows the end of the completed shoe.

Fig. 5 represents a cross section through 40 the toe of a completed shoe.

Fig. 6 illustrates a molded toe box.

Fig. 7 illustrates a filler.

The upper 10 including the toe cap 11 and the lining 12 are assembled in the usual 45 manner, and the upper is lasted and stitched to the sole by the usual machines. According to my invention, the stitches 13, which unite the upper and the sole, pass through the lining in such manner as to leave loose 50 or unattached the edge of the toe end of the lining. This may be done by cutting a slit 14 in each of the side edges of the lining, as indicated in Fig. 1, and bending the end 55 backward toward the instep. Then, when the upper is stitched to the sole, the lining is secured by the stitches along the sides as

far as the slit 14, the turned back portion being left loose. These slits may have been made in cutting out the lining, or in side lasting, or they may be made by the operator just before the stitching operation. After the various other operations have been completed preparatory to turning the shoe, such operations constituting no part of the present invention, the last 16 is withdrawn, 65 and the shoe is turned inside out, as ordinarily.

Then the toe box is inserted. The box is formed of any material which is sufficiently stiff and resilient, such as split sole 70 leather, leather board, celluloid, stiffened felt or the like, and it is molded under pressure to the desired shape. One of such molded boxes is shown in Fig. 6, and it is indicated by the numeral 17. The inturned 75 bottom marginal portions 18 may be separated more or less as desired. In turning the shoe, the loose toe end of the lining is kept drawn back toward the instep or it may be drawn back after the shoe is turned, 80 it necessarily being in this position when the box is to be inserted in the shoe.

The inner and outer surfaces of the box are coated with a suitable cement or glue, or are otherwise rendered adhesive, and 85 then, either with the operator's fingers or by a suitable implement, the box is inserted into the shoe and is forced tightly into the toe cavity thereof. The loose end of the lining is then forced forward so as smoothly 90 to underlie and adhere to the box. A sole-shaped filler 19 of any suitable material, after being rendered adhesive on its under face, is then inserted in the shoe and adheres to the exposed surfaces of the sole, 95 the marginal portions 18 of the box and the edges of the loose end of the lining, so as to secure in place the box and preferably also the lining. A last or shoe form is then, if desired, inserted in the shoe, and the cap, 100 box and lining are all compacted together until the adhesive sets, which takes a very short time.

To prevent any bunching of material at the extremity of the toe cavity, the lining 105 may be somewhat reduced in length and in width at the toe end, so that it will lap but slightly, if at all, on the bottom marginal portions of the box, and be slightly overlapped by the filler.

As previously indicated, one of the great advantages of my process is that I am able

greatly to diminish the time required for completing each pair of shoes. This in turn reduces the stock in the process of manufacture, and releases capital that would otherwise be invested therein, and, in addition, 5 factory floor space is saved which otherwise would be taken up with shoes being dried out.

So far as I am aware, no turn shoe has 10 heretofore been produced having a toe box, which had been initially molded prior to its assembly in the shoe. Hitherto the boxes have been assembled while flat, and hammered and pressed into shape coincidentally 15 with or subsequent to the attachment of the edges of the upper, box and sole together. By employing a previously or initially molded box, I am able to use one which is substantial and which will hold its shape, 20 and thus preserve the shape of the shoe.

What I claim is:

1. A method of making turn shoes, comprising stitching the upper and lining to the sole, but leaving the toe end of the lining unattached, turning the shoe, inserting a molded toe box in the shoe when the said free end of the lining is withdrawn rearwardly, and then tucking the lining into the interior of the inserted box.
2. A method of making turn shoes, comprising stitching the upper and lining to the sole, but leaving the toe end of the lining unattached, turning the shoe, and inserting a molded toe box between the toe end 35 of the upper and the loose end of the lining.
3. A method of making turn shoes, comprising stitching the upper and lining to the sole, but leaving the toe end of the lining unattached, turning the shoe, inserting a 40 molded toe box between the toe end of the upper and the loose end of the lining, and then securing the loose end of the lining.
4. A method of making turn shoes, comprising stitching the upper and lining to 45 the sole, but leaving the toe end of the lining

loose, turning the shoe, drawing the loose end of the lining heelward, rendering the surfaces of a molded toe box adhesive, inserting said box into the toe cavity of the shoe, returning the loose end of the lining 50 to its normal position to adhere to the inner surface of the box, and inserting a filler in the shoe to overlap the edges of the lining and the bottom portion of the box.

5. A method of making turn shoes which 55 comprises securing the upper to the sole, without a toe box, turning the shoe, and then securing a molded toe box in the shoe.

6. A method of making turn shoes which comprises securing the upper to the sole 60 without a toe box, turning the shoe, and inserting a previously molded toe box between the lining and upper of the shoe.

7. A turn shoe having therein an initially or previously molded toe box in contact with the upper.

8. A turn shoe having therein an initially or previously molded toe box arranged between the lining and the upper.

9. A turn shoe having therein an initially or previously molded toe box, inseam 70 stitches uniting the upper and sole and extending through that part of the lining that is at the rear of the toe box, the toe portion of the lining being arranged inside the toe 75 box.

10. A turn shoe having therein an initially or previously molded toe box provided with an inturned flange, said flange being arranged upon the top face of the sole, a lining 80 the toe portion of which is inside said toe box and which has an inturned marginal portion arranged upon the top face of said flange, and a slip sole the marginal portion of which is arranged to lap over and rest 85 upon said inturned marginal portion of the lining.

In testimony whereof I have affixed my signature.

MILTON L. DODGE.
